ANTISURGE VALVE FOR HYDRAULIC
WOOD GRINDERSPercy Ritchie Sandwell, Vancouver, British
Columbia, Canada

Application September 23, 1948, Serial No. 50,830

5 Claims. (Cl. 121—46.5)

1

This invention relates to new and useful improvements in regulating valves for hydraulically actuated machinery and is particularly useful in connection with hydraulic feed control for the presser feet of pulpwood grinders.

Groundwood paper mills produce wood pulp solely by the mechanical action of large grinders which are frequently hydraulically operated and hydraulically controlled. These grinders may be operated individually or in multiple banks of two, three or more grinders to each bank. Each of the grinders so arranged generally includes a turbine-driven grindstone and one or more pulpwood-charging pockets, each of which includes a reciprocable ram or presser foot for forcing pulpwood from a supply hopper into contact with the surface of the associated grindstone.

Each bank of grinders or even an individual grinder receives a supply of water under substantial pressure from a main water supply through a suitably designed governing device which may be, for example, of the type disclosed in U. S. Letters Patent 1,450,380, granted April 3, 1923, to A. F. Meyer. The primary function of such governing devices is to maintain a continuous flow of operating water to the grinders at such pressures and rates of flow as to maintain substantially uniform grinding load on the grindstones at substantially constant speeds of rotation of the grindstones.

When the presser foot of a grinder pocket has been retracted or backed off to permit recharging the pocket with a new supply of pulpwood the demand for high pressure water from the governor for that particular grinder pocket ceases and the governor must adjust itself to the continuing water demand of all other pockets which remain in feed or grinding operation. This phase of the grinding operations seems to have been satisfactorily handled by known types of governors. However, when such a grinder pocket has been recharged with pulpwood and grinding operations are to be restarted with respect to such pocket, forward or feeding movement of the presser foot is initiated by appropriate movement of the maneuvering control valve of the pocket to admit high-pressure feed water from the governor-controlled supply line. This, of course, causes a momentary drop in pressure in the water feed pipe leading to the pocket which is subsequently offset by an increase in available water due to control action by the governor. When the presser foot pushes the pulpwood into initial pressure contact with the grindstone a temporary but substantial increase in loading pressure is caused for

which the governor cannot immediately compensate. In other words, known governors for pulp grinders operate in such a manner that temporary surge loading on the grindstone cannot be avoided whenever the presser foot is advanced to first bring a new charge of wood into grinding contact with the grindstone.

It is therefore an object of this invention to provide novel means usable in conjunction with a hydraulically operated and controlled pulpwood grinder for eliminating shock loading effects on the grindstones whenever a new charge of wood is just brought into grinding contact therewith by a presser foot.

Another object of this invention is to provide means of the character stated which consists of a control valve assembly which is interposed between the governor and a grinder pocket and which is adapted normally to permit free passage of high pressure water from the governor during the grinding phase and to cut off the flow of high pressure water during the latter part of the feed stroke of the presser foot in the grinder pocket while simultaneously permitting the flow of low pressure water from a separate source to complete the feed stroke of the presser foot.

Another object of this invention is to provide a device of the character described which comprises a three-chambered valve casing having two inlet chambers and an outlet chamber with pressure-controlled disc valves operationally positioned within the chambers to effect change of flow from high pressure water to low pressure water and back to high pressure water.

Another object of this invention is to provide a device of the character stated which is effective to permit the initial flow of high pressure water to the cylinder of a grinder pocket for initiating the feed stroke of a presser foot and which will automatically cut off the flow of high pressure water as soon as the feed stroke of the grinder presser foot has commenced, simultaneously permitting a flow of low pressure water through another chamber of the valve for completing the feed stroke of the presser foot, there being means provided for bleeding high pressure water from the high pressure side of the valve to the low pressure outlet of the valve during and upon completion of the feed stroke of the presser foot so that the pressures between high and low pressure sides may become equalized, and high pressure water may again be admitted to the grinder cylinder for the grinding phase of operations by automatic actuation of the valve discs within the casing.

Another object of this invention is to provide a device of the character stated which is simple in design, economical to manufacture and permits ready adjustment and easy maintenance.

With these and other objects in view, the nature of which will be more apparent, the invention will be more fully understood by reference to the drawings, the accompanying detailed description, and the appended claims.

In the drawings,

Fig. 1 is a fragmentary view, partly in section, showing one end of the presser foot actuating cylinder of a grinder pocket together with its associated control valves and the intermediate surge load eliminating valve with which this invention is particularly concerned, the valves all being shown in the positions for starting a feed stroke of a grinder pocket presser foot;

Fig. 2 is an enlarged longitudinal section of the surge load eliminating valve constructed in accordance with this invention and shows its component parts in the position assumed during the middle portion of the feed stroke of a grinder pocket presser foot;

Fig. 3 is a view similar to Fig. 2 but shows the component parts of the valve assembly in the positions taken after the completion of the feed stroke of a presser foot when high pressure water is again being admitted to the cylinder; and

Fig. 4 is a view similar to Fig. 1 but shows the parts in the position during backing off of the grinder pocket presser foot with the piston being shown as it approaches the end of its retractive or backing off stroke.

By reference to the drawings in detail it will be seen that this invention is applied to a hydraulic grinder with only those parts of the grinder which are pertinent to this invention being shown in detail. By reference to Figs. 1 and 4 of the drawings it will be seen that a cylinder generally indicated at 5 having a cylinder head 6, a feed stroke water passage 7 and a backing off water passage 8 is provided with a piston 9 to which is rigidly affixed a piston rod or ram 10. The other end of the piston rod 10 passes through a gland in the opposite end of the cylinder 5 (not shown) and carries the usual presser foot (not shown) for forcing pulpwood into contact with the grindstone. Since the general assembly of hydraulic pulpwood grinders is well known to those skilled in the art no attempt has been made herein to illustrate the complete grinder.

Immediately below the cylinder 5 is a piston control valve assembly generally indicated at 11 which includes a casing 12 having an inlet port indicated by dotted lines at 13 for admitting feed stroke and grinding pressure water and a second inlet port indicated by dotted lines at 14 for admitting backing off water. This control valve assembly may be considered as typical of this art in that the passage of water from either of the inlet ports 13 and 14 to respectively corresponding outlet passages 15 and 16 occurs through either pair of annular chambers 17, 17 or 18, 18 in accordance with the position of a dual valve piston generally indicated at 19 which is reciprocally mounted within a suitably apertured bushing sleeve 20. The dual piston 19 carries a piston rod 21 which extends outwardly beyond the casing 12 through a spacing spider 22 into an actuating cylinder 23. A double faced valve actuating piston 24 is mounted on the outer end of the rod 21 within the cylinder 23. Inlet ports 25 and 26 are located adjacent the respective ends

of the cylinder 23 and serve to admit low pressure water to either end of the cylinder for valve operating purposes from a supply of low pressure water which passes through a master control or maneuvering valve generally indicated at 27.

The maneuvering valve 27 is also a piston valve and includes an outer casing 28, an internal reciprocable piston 29, an inlet port indicated by dotted lines at 30 and a pair of outlet passages 31 and 32. The piston is carried by a piston rod 33 which passes through a gland 34 and is operably connected to a control handle 35 through appropriate connecting links.

The surge load eliminating valve which is constructed in accordance with the instant invention is preferably placed below the control valve assembly 11 as indicated in Figs. 1 and 4 of the drawings. This valve comprises a casing 36 having a large internal chamber divided into a left-hand portion 37, a right-hand portion 38 and a centrally disposed annular discharge portion 39. An inlet port 40 is in open communication with the chamber portion 37 and a similar inlet port 41 is in open communication with the chamber portion 38. A centrally disposed disc 42 having an aperture 43 forms one wall of the annular chamber 39 and a similar disc 44 having an aperture 45 forms another wall of the annular chamber 39. One wall portion of the chamber section 37 is closed by a removable plug 46 having an inwardly projecting stud 47 formed integral therewith. The stud portion 47 is provided with a counter bore 48 and a bushing 49.

A valve stem 50 which has a reduced end portion 51 slidably carried by the bushing 49 is provided at its other end with a similarly reduced end portion 52 slidably carried in a bushing 53 mounted in an inwardly projecting stud portion 54 of a removable plug 55 closing off one wall portion of the chamber portion 38.

Within the chamber 37 the valve stem 52 carries a shouldered collar 56 which is adapted to receive one end of a compression spring 57, the other end of which is seated adjacent the base of the inwardly projecting stud 47 of the end plug 46. Thus the compression spring 57 will always tend to force a movement of the valve stem 50 to the right as viewed in all of the figures of the drawings. A valve disc 58 is rigidly affixed to the valve stem 50 within the chamber portion 38 and is adapted to be seated on the adjacent face of the disc 44 and thus control flow of fluid through the aperture 45. A similar valve disc 59 is freely mounted on the central portion of the valve stem 50 within the space between the discs 42 and 44 and is adapted to seat on the adjacent face of the disc 42 and thus control passage of fluid through the aperture 43. A compression spring 60 surrounds the valve stem 50 and extends between the rigidly affixed valve disc 58 and the freely movable valve disc 59 and thus tends to constantly urge the valve disc 59 towards seating contact with the disc 42.

The upper wall portion of the chamber 38 is provided with a vertically disposed bore 61 which extends into open communication with a horizontally disposed bore 62 which in turn opens into communication with the discharge area of the annular chamber portion 39. The outer end of the bore 62 is closed by a removable plug 63. A needle valve 64 is threadably engaged in the upper portion of the casing 26 and is disposed in alignment with the vertically arranged bore 61 so that the pointed needle end thereof may be-

come seated at the juncture between the bores 61 and 62 or may be slightly spaced therefrom in order to permit a restricted flow of fluid from the chamber portion 38 into the discharge section 39. The needle valve 64 may be locked into any desired position as through the medium of a lock nut 65.

It may have been observed from the foregoing description that the hydraulic system as herein disclosed is designed for operation by both low pressure and high pressure water. The maneuvering valve 27 receives low pressure water from a source of supply and transmits it to the actuating cylinder 23 of the piston control valve assembly 11. This portion of the low pressure water, incidentally, also actuates the charging door (not shown) of the wood supply hopper which is located adjacent the grinder pocket through mechanisms which are contained in a cylinder generally indicated at 63 which is disposed in parallelism with the main presser foot actuating cylinder 5. In this system low pressure water is also always used for the backing off movement of the presser foot to permit a recharging of the grinder pocket with fresh wood. In so far as the feed stroke of the presser foot is concerned that motion is initiated by high pressure water and as soon as feeding motion of the piston 9 has commenced a pressure drop within the cylinder will cause the high pressure water to be cut off and low pressure water to be admitted until the feeding stroke of the presser foot has been completed. At this time the low pressure water is cut off from the feeding end of the cylinder 5 and high pressure water again admitted in order to maintain full grinding pressure. The flow diagram for the piping to effect these general operations is indicated on the drawings by dotted lines. Low pressure water is received from a suitable source of supply through the medium of a pipe 67 which may connect directly with the inlet port 49 of the surge load control valve assembly. A pipe 68 may branch off from the pipe 67 and lead up to the intake port 30 of the maneuvering valve 27. Another pipe 69 may branch off from the pipe 68 and lead to the inlet port 14 of the piston control valve assembly 11. From the maneuvering valve 27 the low pressure water is admitted to the port 26 of the piston valve actuating cylinder 23 through a pipe 70 and in a similar manner water is carried from the maneuvering valve to the port 25 through a pipe 71. High pressure water from the governor is connected to the system through a pipe 72 which may be directly connected to the inlet port 41 of the surge load control valve assembly. Pipe 73 connects the discharge port 39 of the surge load control valve assembly with the inlet port 13 of the piston valve assembly 11. It may be of interest to note the typical water pressures which may be employed in hydraulic grinder systems of this nature, namely, a low pressure water on the order of 40 lbs. per square inch and high pressure water on the order of 100 lbs. per square inch. With a pressure differential of this nature it has been found that the surge load control valve operates quite satisfactorily and that through the use of low pressure water of this indicated pressure to effect at least the latter portion of the feed stroke of the presser foot no abnormal surge loading is met with on the grindstone.

Hydraulic grinder systems of this type described herein may be considered to operate through three phases in a complete grinding cycle. The

first phase is the charging or feeding phase in which the grinder pocket presser foot pushes a new charge of pulpwood into contact with the grindstone. The second phase may be termed the grinding phase and during this period full grinding pressure is applied by the presser foot. The third phase is the backing off phase during which the presser foot is retracted so that a fresh supply of pulpwood may be introduced into the grinder pocket. In Fig. 1 of the drawing the parts are all shown in the position to initiate the first phase of the cyclic operation outlined above.

With the maneuvering valve 27 being in the position indicated in Fig. 1 the low pressure water flows through its outlet port 31 down through the pipe 70 and into the cylinder 23 through the inlet port 26, thus causing the piston 24 to be moved to the extreme right of its limit of movement and correspondingly effecting the positioning of the dual piston valve 19 to permit a flow of water into the feed stroke water passage 7 of the main cylinder 5. The elements of the surge load control valve assembly at this instant are in the positions indicated in Fig. 1 and high pressure water will flow from the pipe indicated at 72 through the inlet port 41, the right-hand chamber 38, and since the valve disc 58 is raised from its seated position relative to the seating disc 44 the water will flow through the aperture 45 into the discharge passage 39. No high pressure water can flow through the aperture 43 since the pressure differential between the chamber portions 37 and 39 is such that the high pressure water flowing through the chamber portion 39 will effectively keep the valve disc 59 seated. This high pressure water will flow from the control valve assembly through the pipe 73 into the inlet 13 of the valve assembly 11, and consequently it is this high pressure water which initially starts a motion of the piston 9 and its associated presser foot. As soon as this forward feeding movement of the piston 9 starts under the influence of high pressure water a pressure drop is caused in the line between the inlet port 41 of the surge load control valve and the piston. This pressure drop will effect a pressure differential between the chamber portions 38 and 39 of the surge load control valve assembly sufficient to cause the valve disc 58 to become seated on its seating disc 44 against the action of the spring 57, thus closing off the aperture 45 and preventing the flow of any more high pressure water to the main cylinder 5. Since the flow of high pressure water from the chamber 38 is prevented by the closing of the valve disc 58 low pressure water in the chamber 37 becomes effective to raise the valve disc 59 off its seat against the action of the spring 69 to permit the flow of low pressure water into the discharge chamber passage 39 and thus into the main cylinder 5 through the control valve assembly 11. In this manner further feed motion of the presser foot is effected solely by low pressure water. Fig. 2 of the drawings indicates the positions of the various elements of the surge load control valve assembly during this portion of the feed stroke.

When the piston 9 of the main cylinder and its associated presser foot have moved forward a sufficient distance to push the fresh charge of pulpwood into contact with the grindstone initial grindstone pressure is effected only by low pressure water since that is the only water available to act on the head of the piston 9 at this particular instant of time. The low pres-

sure water does not develop sufficient grinding pressure to appreciably move the presser foot forward and consequently the flow of water through the system into the cylinder 5 substantially ceases. At this time high pressure water from the chamber 38 which has been bleeding through from the chamber 38 to the chamber 39 via the bores 61 and 62 under the restrictive control of the needle valve 64 becomes effective through the bleeding action to approximately 10 equalize the pressures between the chamber 38 and the chamber 39. As the pressures approach equality the spring 57 becomes effective to unseat the valve disc 58 and again permit the flow of high pressure water through the aperture 45 into the discharge chamber 39. This flow of high pressure water, of course, will also effect a seating of the disc valve 59 and prevent the flow of high pressure water into the low pressure water chamber portion 37. Fig. 3 of the drawings illustrates the position of the several elements of the surge load control valve at this point in the operations. With the flow of high pressure water again taking place full grinding pressure is restored to the presser foot and normal grinding continues.

When it becomes necessary to recharge the grinder pocket with fresh pulpwood the maneuvering valve 27 is shifted to the position indicated in Fig. 4 of the drawings so that low pressure water will flow through the outlet passage 32 and the pipe 71 into the cylinder 23 through its inlet port 25. Thus the actuating piston 24 will be forced to move to the extreme left of its limited movement as viewed in Fig. 4, and the dual valve piston 19 will partake of a corresponding movement to cut off the flow of water into the passage 7 of the main cylinder assembly 5 and initiate the flow of low pressure backing off water through the passage 8. The low pressure backing off water is received through the inlet port 14 of the valve assembly 11 and of course flows into the passage 8 and from there into the cylinder 5 and acts on the left-hand face of the piston 9 to impart the backing off movement to it and its associated presser foot. As the piston is thus being retracted the water which is at the head of the piston and in the passage 7 is discharged through an exhaust duct or passage 14 in the control valve casing 12 and a discharge pipe indicated by dotted lines at 75. In a like manner the spent water from the maneuvering valve 27 is discharged through an exhaust passage 76 and a discharge pipe indicated by dotted lines at 77. During the backing off movement of the presser foot as outlined above the several elements of the surge load control valve are in the positions indicated in Fig. 4 which are identical to the positions illustrated in Fig. 3. No movement of the valve disc elements of this surge load control assembly can take place since the dual piston 19 of the control valve 11 effectively closes off passage of any water from its inlet port 13 to any other portion of the system. Obviously, unless water could flow through the port 13 and the control valve assembly 11 no water can flow through the surge load control valve assembly, and the parts must remain in a static condition.

Thus it will be seen that the invention disclosed herein provides novel means particularly useful in hydraulically controlled pulpwood grinders in which certain operative steps are effected through the use of low pressure water

and other operative steps are effected through high pressure water; and in which high pressure water is employed to initiate the feeding stroke of a presser foot and as soon as the feed stroke has been initiated will cause an automatic shift from high pressure water to low pressure water for the purpose of completing the feed stroke; and which becomes thereafter effective to again admit high pressure water for the grinding phase.

It is, of course, to be understood that various details of arrangements and proportions of parts may be modified within the scope of the appended claims.

I claim:

1. A surge-load preventing valve for hydraulic grinders comprising a casing having a lateral chamber extending into open communication with a centrally disposed annular chamber, a first inlet port formed in said casing adjacent one end of said lateral chamber and adapted to be connected to a source of high pressure water, a second inlet port formed in said casing adjacent the other end of said lateral chamber and adapted to be connected to a source of low pressure water, 20 a discharge port formed in said casing and extending into open communication with said annular chamber, a pair of spaced annular valve seats rigidly affixed to said casing within the central portion of said lateral chamber and effective to divide said chamber into a high pressure portion, a low pressure portion and a centrally located discharge portion, a valve stem reciprocably mounted within said lateral chamber and extending through said valve seats, a biasing spring connected with said valve stem and effective to constantly urge it toward the high pressure portion of said chamber, a valve disc rigidly affixed to said stem within said high pressure chamber portion and adapted to be seated on one of said annular valve seats, a second valve disc freely mounted on said valve stem and positioned intermediate said valve seats and being adapted to be seated on the other of said valve seats, and a biasing spring interposed between said first and second valve discs and effective to constantly urge said second valve disc toward seating engagement with its associated valve seat, said casing being provided with a bleeder duct extending between said high pressure and annular chamber portions whereby to effect substantial equalization of pressures therebetween after such times as said first valve disc has become seated on its associated valve seat and said second valve disc has become unseated to permit passage of low pressure water to said discharge port.

2. A surge-load preventing valve for hydraulic grinders comprising a casing having a lateral chamber extending into open communication with a centrally disposed annular chamber, a first inlet port formed in said casing adjacent one end of said lateral chamber and adapted to be connected to a source of high pressure water, a second inlet port formed in said casing adjacent the other end of said lateral chamber and adapted to be connected to a source of low pressure water, 40 a discharge port formed in said casing and extending into open communication with said annular chamber, a pair of spaced annular valve seats rigidly affixed to said casing within the central portion of said lateral chamber and effective to divide said chamber into a high pressure portion, a low pressure portion and a centrally located discharge portion, a valve stem reciprocably mounted within said lateral chamber and extending through said valve seats, a biasing spring connected with said valve stem and effective to constantly urge it toward the high pressure portion of said chamber, a valve disc rigidly affixed to said stem within said high pressure chamber portion and adapted to be seated on one of said annular valve seats, a second valve disc freely mounted on said valve stem and positioned intermediate said valve seats and being adapted to be seated on the other of said valve seats, and a biasing spring interposed between said first and second valve discs and effective to constantly urge said second valve disc toward seating engagement with its associated valve seat, said casing being provided with a bleeder duct extending between said high pressure and annular chamber portions whereby to effect substantial equalization of pressures therebetween after such times as said first valve disc has become seated on its associated valve seat and said second valve disc has become unseated to permit passage of low pressure water to said discharge port.

spring connected with said valve stem and effective to constantly urge it toward the high pressure portion of said chamber, a valve disc rigidly affixed to said stem within said high pressure chamber portion and adapted to be seated on one of said annular valve seats, a second valve disc freely mounted on said valve stem and positioned intermediate said valve seats and being adapted to be seated on the other of said valve seats, a biasing spring interposed between said first and second valve discs and effective to constantly urge said second valve disc toward seating engagement with its associated valve seat, said casing being provided with a bleeder duct extending between said high pressure and annular chamber portions whereby to effect substantial equalization of pressures therebetween after such times as said first valve disc has become seated on its associated valve seat and said second valve disc has become unseated to permit passage of low pressure water to said discharge port, and means for regulating the flow of fluid passing through said bleeder duct.

3. A surge-load preventing valve for hydraulic grinders comprising a casing having a lateral chamber extending into open communication with a centrally disposed annular chamber, a first inlet port formed in said casing adjacent one end of said lateral chamber and adapted to be connected to a source of high pressure water, a second inlet port formed in said casing adjacent the other end of said lateral chamber and adapted to be connected to a source of low pressure water, a discharge port formed in said casing and extending into open communication with said annular chamber, a pair of spaced annular valve seats rigidly affixed to said casing within the central portion of said lateral chamber and effective to divide said chamber into a high pressure portion, a low pressure portion and a centrally located discharge portion, a valve stem reciprocably mounted within said lateral chamber and extending through said valve seats, a biasing spring connected with said valve stem and effective to constantly urge it toward the high pressure portion of said chamber, a valve disc rigidly affixed to said stem within said high pressure chamber portion and adapted to be seated on one of said annular valve seats, a second valve disc freely mounted on said valve stem and positioned intermediate said valve seats and being adapted to be seated on the other of said valve seats, a biasing spring interposed between said first and second valve discs and effective to constantly urge said second valve disc toward seating engagement with its associated valve seat, said casing being provided with a bleeder duct extending between said high pressure and annular chamber portions whereby to effect substantial equalization of pressures therebetween after such times as said first valve disc has become seated on its associated valve seat and said second valve disc has become unseated to permit passage of low pressure water to said discharge port, and a needle valve threadably engaged in said casing for regulating the flow of fluid passing through said bleeder duct.

4. In a hydraulic grinder wherein is provided a cylinder, a presser foot piston slidably carried within said cylinder, a high pressure water connection communicating with one end of said cylinder for normally imparting a feed stroke to said presser foot piston in one direction, a low pressure water connection communicating with the other end of said cylinder for normally ef-

fecting a retractive stroke to said presser foot piston in the opposite direction, and a master control valve connected with said low pressure water line for controlling the direction of movement of said presser foot piston; the combination of a surge-load preventing valve including a casing having an inlet port connected with a high pressure water line, a second inlet port connected with said low pressure water line, a discharge port connected to the high pressure end of said cylinder, a pair of spaced annular valve seats secured within said casing and dividing the interior thereof into a high pressure chamber, a low pressure chamber and a discharge chamber, a first valve disc positioned within said discharge chamber and operably associated with one of said valve seats for controlling passage of fluid from said low pressure chamber to said discharge chamber, a second valve disc positioned within said high pressure chamber and operably associated with the other of said valve seats for controlling passage of fluid from said high pressure chamber to said discharge chamber, spring means for biasing said second valve disc away from seating contact with its associated valve seat, and spring means extending between said valve discs for biasing said first valve disc toward seating contact with its associated valve seat, said valve discs being operable by fluid pressure and being automatically effective in accordance with variations of pressure within said casing, first to permit high pressure water to flow into said cylinder when said master control valve has been positioned to initiate a feed stroke of said presser foot piston, secondly to close off the flow of high pressure water to said cylinder at such time as a pressure drop occurs in the said high pressure line during the feed stroke of said presser foot piston and simultaneously to admit low pressure water to continue said feed stroke of said presser foot piston, and finally upon completion of the feed stroke of said presser foot piston to again admit high pressure water to said cylinder so that full mechanical pressure may be applied by said presser foot piston, said valve casing being provided with a bleeder passage extending between said high pressure and discharge chambers.

5. A surge-load preventing valve for hydraulic grinders comprising a casing having a lateral chamber extending into open communication with a centrally disposed annular chamber, a first inlet port formed in said casing adjacent one end of said lateral chamber and adapted to be connected to a source of high pressure water, a second inlet port formed in said casing adjacent the other end of said lateral chamber and adapted to be connected to a source of low pressure water, a discharge port formed in said casing and extending into open communication with said annular chamber, a pair of spaced annular valve seats affixed to said casing within the central portion of said lateral chamber and dividing the interior thereof into a high pressure chamber, a low pressure chamber and a discharge chamber; a first valve disc positioned within said discharge chamber and operably associated with one of said valve seats for controlling passage of fluid from said low pressure chamber to said discharge chamber, a second valve disc positioned within said high pressure chamber and operably associated with the other of said valve seats for controlling passage of fluid from said high pressure chamber to said discharge chamber, spring means for biasing said

11

second valve disc away from seating contact with its associated valve seat, and spring means extending between said valve discs for biasing said first valve disc toward seating contact with its associated valve seat, said valve discs being operable by fluid pressure and being automatically effective in accordance with variations of pressure within said casing, first to permit a flow of high pressure water through said high pressure and discharge chambers while preventing any flow of low pressure water through said low pressure chamber and being automatically operable upon the occurrence of a pressure drop occurring through said discharge port to effect the shutting off of high pressure water and the admission of low pressure water, and finally being automatically operable upon substantial equalization of pressures between said discharge and high pressure chambers to again permit the flow of high pressure water and the shutting off of low pressure water, said casing being provided with a bleeder passage extending between said high

5 pressure and discharge chambers whereby the pressures therebetween may become gradually equalized during such times as high pressure water is directly cut off from said discharge chamber and low pressure water is admitted thereto.
